CAB-OVER-ENGINE GEARSHIFT MEANS

George M. Beimer, Lodi, N. J., assignor to Couse Laboratories, Inc., Newark, N. J., a corporation of New Jersey

Application December 24, 1940, Serial No. 371,535

6 Claims. (Cl. 74—473)

This invention relates to a new and improved type of hand gear shift especially adapted to be used in cab-over-engine construction.

In the early forms of trucks, the driver's seat or cab was placed back of the engine in about the same manner as in automobiles; that is to say, substantially over the transmission located in the rear of the engine. In order to get more room for the truck body, later designs of trucks have moved the cab forward over the engine and this has brought about some complications in the gear-shift arrangement. The usual practice for this arrangement is to use a hand-shifting lever connected to a selector box from which a plurality of rods, usually two, extend rearwardly from the selector box back to the transmission.

It is the object of my present invention to greatly simplify this kind of gear-shift and thereby cheapen the construction.

Another object of my invention is to provide a new type of gear-shift having its parts very accessible, easily and cheaply maintained and easily operated.

Another object of my invention is to provide a simplified gear-shift for cab-over-engine construction which may be readily adapted for right or left-hand driving.

A further object of my invention is to provide a gear-shift control for the special purpose described in which the parts are so constructed as to overcome all lost motion and thereby aid in the accuracy of the translation of the movements of the hand to the engine transmission.

My improved type of gear-shift mechanism will be understood by reference to the annexed drawings wherein:

Figure 1 is a side elevation of the apparatus as installed on an engine and its transmission.

Figure 2 is a view looking down on Figure 1 with the cab removed from the engine.

Figure 3 is a view on the line 3—3 of Figure 1.

Figure 4 is a view, part in elevation and part in section, of the hand lever and also showing the portion of the connecting rod which is actuated by the hand lever.

Figure 5 is a view on the line 5—5 of Figure 4.

Figure 6 is a view on the line 6—6 of Figure 4.

Figure 7 is a view similar to Figure 4, but taken at right angles thereto.

Figure 8 is a view on the line 8—8 of Figure 1.

Figure 9 is a view on the line 9—9 of Figure 8.

Figure 10 is a view on the line 10—10 of Figure 9.

Figure 11 is a view on the line 11—11 of Figure 8.

Figure 12 is a view on the line 12—12 of Figure 1.

Figure 13 is a view on the line 13—13 of Figure 12.

Figure 14 is a view on the line 14—14 of Figure 15.

Figure 15 is a view on the line 15—15 of Figure 12.

Figure 16 is a view similar to Figure 2, but showing a modified form of construction.

In the various views, wherein like numbers refer to corresponding parts, 1 is an engine having a driver's seat or cab 2 positioned thereover. Mounted on the side of the engine 1 is a bracket 3 having a stud 4 projecting therefrom. The stud 4 is hollow and positioned within the base of the hollow portion is a spring 5, against which rests a bearing member 6 provided with a short stem 7 projecting within the spring 5 to centralize and guide it.

A screw-threaded member 8 is threaded into the outer end of the stud 4 and is provided with a cup-shaped recess to receive one side of a ball 9 of a lever 10. There is a hole 47 in the side wall of the stud 4 large enough to pass the spherical end 9 of the lever; so by inserting a tool under the bearing member 6 and pushing the same away from the lever, the same may be readily disconnected from its pivotal mounting. To expedite this operation, a notch 48 is provided to make room for the tool, thereby insuring that the bearing 6 may be moved far enough to allow the quick withdrawal of the pull end of the lever. However, for normal operation, the arcuate or conical surfaces of the bearing member 6 and the inner end of the screw 8, together with the adjustment of the screw 8, are such as to prevent the lever from being accidentally drawn from its seat. The lever 10 has a hand-grip knob 11 for operating the lever which, as just described, is pivotally mounted through the medium of the ball 9 between the bearing member 6 and the cup recess in the screw 8.

The knob 11 has a threaded stem 12 screwed into the upper end of the lever 10. A finger latch 13 is positioned on the outer surface and at the end of the lever 10, and has a pin 14 operatively located in a slot 15 in the side wall of the hollow lever 10. The pin 14 projects into a block 16 and is fastened therein by a screw stud 17 which is reached through the end of the lever 10 when the knob 11 is removed.

Positioned between the block 16 and the threaded end 12 of the knob is a spring 18 which is quite strongly compressed by the knob 11 when

it is screwed into position in the lever 10. Connected to the block 16 by means of a stud 19 is a flexible cable or Bowden wire 20. The stud 19 is held in place by a set screw 21. It will be seen that all of these parts are readily accessible on removing the knob 11 for the purpose of assembly or disassembly.

The lever 10 is hollow for a considerable distance of its length from the grip to at least down to the point 22. From the point 22 down to the ball 9 the lever may be of solid material and welded at the point 22 to a flattened area of the tubular lever 10, but in either case, whether the lever 10 be hollow all the way down to the ball end 9, or solid from the point 22 down to the ball 9, there is a flat portion 23 formed in the lever. The flat portion 23 has considerable surface area to make a large bearing surface for the two parts 24 and 25 of the hollow connecting rod 26 which is pivoted by the stud or pin 27 which preferably has an integral head 28 at one end, and a hole for a cotter pin 29 at the other end, a washer 30 being used between the cotter pin and the flange 25. The flange portions 24 and 25 are also of considerable area and fit snugly the opposite sides of the flat portion 23 of the lever 10, thereby producing a pivotal joint having large laterally engaging surfaces which eliminate all lost motion at this joint.

The connecting rod 26, as indicated in Figures 2 and 3, extends diagonally inwardly from the pivot point 27 to a point over or adjacent the transmission 31. The transmission has a gear-shift member 32 from which extends a connecting stud 33 terminating in a portion 34 having considerable area to cooperate with the flanges 35 and 36 of the connecting rod 26. The flanges 35 and 36 are, similar to the flanges 24 and 25, of considerable area and fit snugly around the portion 34 which is pivotally mounted on the pin or stud 37, having a head 38 which is preferably welded to a plate 39 which, in turn, is fastened as by a screw 40 to the flange 38. The stud 37 is held in place by a washer 41 and a cotter pin 42.

The head 38 of the stud 37 has a clearance hole therein for the cable or wire 20 which passes through an orifice 43 closely adjacent the pivot 27 and into the connecting rod 26 and comes through a hole 44 adjacent the plate 39, and on through the hole in the head of the pin 37 and into the transmission 31 by way of the gear-shift 32 and a recess 45 formed in the stud 33. The end of the wire 20 engages a latch within the transmission to lock the member 33 in reverse position only; otherwise, the gear-shift is standard. Since this latch and the internal mechanism of the transmission form no part of the present invention, they are not further described herein.

Suffice it to say that the spring 18, acting against the block 16, pushes on the wire 20 and holds the latch within the transmission continuously in locking position, so when it is necessary to shift gears, the latch 13 is pulled upwardly to release the latch in the transmission and thereby hold the gear-shift lever 10 and the connecting rod 26 to be operated, to shift the member 33 and thereby the gears within the transmission. On releasing the latch 13, the spring 18 will cause the latch in the transmission to lock the gears in the shifted position.

While the wire 20 is flexible, it has material stiffness longitudinally of its length. By passing the wire 20 through the hollow part of the lever 10 and the hollow connecting rod 26, it is concealed for very nearly all of its length and is

thus protected from injury or misplacement, and is so guided through the opening 43 and the cut-away portions at the lever end of the connecting rod 26, and the orifice 44 at the opposite end of the connecting rod and through the guide hole in the head 38 of the pin 37, that it may be easily operated to control the latch associated with the transmission.

As shown in Figure 16, the support for the lower end of the shift lever 10 may be mounted on some part of the chassis or body of the truck instead of on the engine, in which case a different style of bracket, as illustrated at 46, is used, but the gear-shift lever 10 will be substantially the same as heretofore described.

It will be readily seen, from what has been said, that the gear-shift lever may be mounted on either side of the engine for right or left-hand operation. Furthermore, certain of the details may be varied without departing from the spirit of my invention or the scope of the appended claims.

What I claim is:

1. A cab-over-engine gear-shift means, comprising an operating lever having a hand grip, a pivotal support for the lever at a position to one side of the engine and below the cab, the said lever terminating in a spherical formation while the said support comprises a bracket having a projecting hollow stud with a hole in its wall large enough to pass the spherical formation of the lever, a spring-pressed bearing member engaging the said formation on one side and a screw in the end of the stud having a bearing surface engaging said lever formation on the side opposite to said spring-pressed member, a connecting rod having one end pivotally connected to said lever intermediate its ends and extending diagonally inwardly to a point adjacent the transmission and terminating in an end having two large flat surfaces, a gear shifting member going into the transmission and extending upwardly from the transmission and terminating in a member having a relatively large flat surface for engagement with said large flat surface on the end of the connecting rod, a pivot pin going through all of said surfaces and non-rotatably fastened to the rod, the pin having a guide hole in one end, a latch-pull carried by said lever adjacent the hand grip and a flexible pull-wire having considerable stiffness longitudinally of its length fastened to the latch-pull and extending along the lever and connecting rod and through said guide hole in said pin to a latch at the transmission.

2. A cab-over-engine gear-shift means, comprising an operating lever having a hand grip, a pivotal support for the lever at a position to one side of the engine and below the cab, said lever being hollow from the hand grip to at least a point a considerable distance below the grip, the lever having a flat portion of substantial area intercepting the hollow part, a hollow connecting rod having spaced flanges of considerable area fitting on opposite sides of said lever flat portion and pivoted thereto, the rod also having spaced flanges at its opposite end, a gear-shift member extending from a transmission and having a portion with relatively large oppositely disposed surfaces fitting between the last-mentioned flanges of the connecting rod, a pin for holding these flanges and gear-shift member parts together, a latch-pull slidably carried by said lever adjacent the grip and a pull-wire operatively attached to the latch-pull and extending through the hol-

low part of the lever into the hollow rod and thence directly to a latch associated with the transmission.

3. A gear-shift means as set forth in claim 2, further defined in that the operative attachment between the pull-wire and latch-pull includes a block fitting within the upper end of the said lever, a pin going into both the block and latch-pull, releasable means carried by the block for holding the pin in place, and means for anchor- 10 ing the pull-wire to the block.

4. A gear-shift means as set forth in claim 2, further defined in that the operative attachment between the pull-wire and latch-pull includes a block fitting within the upper end of the said 15 lever, a pin going into both the block and latch-pull, releasable means carried by the block for holding the pin in place, means for anchoring the pull-wire to the block, and a spring between the block and hand grip for normally holding the latch-pull and pull-wire in latching position.

5. A gear shift means as set forth in claim 1 further defined in that, the wall of the hole in said stud toward the spring has a notch therein 20 to provide space for a lifting tool which may be used to force the spring-pressed bearing mem- 25

ber away from the spherical formation of the lever whereby a quick disconnection of the lever from its bearing may be assured.

6. A transmission gear-shift means including a lever having a hand grip at its free end and pivotally mounted at a considerable distance from the transmission, a connecting rod pivotally connected to the lever intermediate its ends through the medium of large-area closely-engaging surfaces with a pivot pin passing therethrough, a gear-shifting member going into the transmission and having its outer end jointed to the said rod through closely inter-engaging surfaces with a joint pin going therethrough, a latch-pull slidably carried on the free end of the lever, cooperative means within the lever and fastened to the latch-pull, a stiff wire or cable attached to said cooperative means and extending through the lever to a point near the rod pivot thereon where it leaves the lever and enters the rod through which it extends to a point near the opposite end of the rod, and means for guiding the wire or cable from the rod downwardly to a latch in the transmission.

GEORGE M. BEIMER.
